THERMAL RETARDER

Clark M. Osterheld, Stoughton, Wis., assignor to
 McGraw Electric Company, Elgin, Ill., a corporation of Delaware

Application August 24, 1946, Serial No. 692,900

14 Claims. (Cl. 219—39)

1

My invention relates to thermal retarders and more particularly to water heater control systems comprising a specific form of thermal retarder.

An object of my invention is to provide a water heater circuit control system embodying a novel form of thermal retarder.

Another object of my invention is to provide a water heater control system for causing immediate energization of the electric heater for a hot water tank that shall be effective to cause immediate energization of an electric heater after a time-controlled switch is closed at the start of an off-peak period and in case the tank is full of cold water.

Another object of my invention is to provide a water heater control system for causing energization of the electric heater of a hot water tank with a predetermined adjustable time period of delay upon closing of a time-controlled switch in case only a relatively small amount of cold water is in the tank at that time.

Other objects of my invention will either be apparent from a description of one form of system embodying my invention or will be pointed out in the course of such description and set forth in the appended claims.

In the drawing,

The single figure is a view in vertical, longitudinal section through a domestic hot water tank having operatively associated therewith a thermal retarder embodying my invention.

I have shown a tank 11 having a lower closure member 13 which is provided with a cold water inlet pipe 15 as well as an upper closure member 17 having therein a hot water outlet pipe 19. The tank 11 is surrounded by a mass 21 of heat-insulating material such as mineral wool, which is held in proper operative position by an outer casing 23. I prefer to provide a single electric heater 25 which may be of a kind now in use and be clamped against the outer surface of the lower end portion of the tank and be positioned in a tunnel 27.

I provide a thermally-actuable switch mounted on the tank 11 adjacent to the lower end thereof, this switch including a bimetal bar 29, the fixed end of which is mounted on a fixed contact member 31 while the upper end thereof is adapted to be engaged with and disengaged from a second contact 33. Bimetal bar 29 is so designed, constructed and adjusted that it will be in engagement with contact 33 when it is subject to cold water and that it will be disengaged from contact 33 when subject to hot water.

2

By cold water I mean water the temperature of which may vary between the limits of 70° to a temperature value on the order of 130°, while by hot water I mean water the temperature of which is on the order of 150° F.

I provide a second thermally-actuable switch for controlling the energization of heater 25, this switch comprising a bimetal bar 35, the fixed end of which is mounted on a contact 37 while its free end is adapted to be engaged with and be disengaged from a second fixed contact member 39. While the second or upper thermally-controlled switch may be positioned anywhere along the tank 11 intermediate its ends, I prefer to mount it in heat-receiving relation with tank 11 at about the middle of its height.

I provide also a time-controlled switch comprising a first contact arm 41 and a second contact arm 43, these contact arms being adapted to be held out of engagement with each other during all on-peak hours during a twenty-four-hour day and are to be held in engagement with each other on all off-peak periods of a twenty-four-hour day.

For illustration I may state that where only one off-peak period is used, it will extend from about 10:00 P. M. or 11:00 P. M. to about 6:00 A. M. the following morning.

A novel form of thermal retarder 45 comprises a tubular member 47 which may be made of a high-heat-conducting material such as brass, copper or aluminum and which tube is closed at the bottom end and open at the top. At the top there is secured to the open end a bellows 49 which is closed at its upper end by a metal plate 51. I provide a fluid 53, such as water, in the container 47, which fluid is adapted to be vaporized by means to be hereinafter described so that the bellows 49 will be caused to expand with results to be hereinafter set forth.

A small wattage heating coil 55 is insulated on and around the tube 47. By small wattage I mean a coil in which the amount of energy translated into heat is on the order of 5 to 10 watts and in which it is possible to vary the exact amount of energy translated into heat.

I provide a pair of supply circuit conductors 57 and 59 of which conductor 57 is connected with contact arm 41. Contact arm 43 is connected by a conductor 61 to contact 39. Contact 37 is connected by a conductor 63 to a conductor 65 which extends from one contact member 67 of a pair including a second fixed contact member 69 which are adapted to be engaged with and be disengaged from a contact bridging member 71.

which is insulatedly mounted on closure plate 51 of bellows 49. The other end of conductor 65 is connected with one terminal of the electric heater 25, the other terminal of which is connected by a conductor 72 to contact 33. Contact 31 is connected by a conductor 73 with the second supply circuit conductor 59. A conductor 75 connects fixed contact member 69 and conductor 61 to one terminal of the low wattage heating coil 55, the other terminal of which is connected to one terminal of an adjustable rheostat 77, the other movable terminal 79 being connected by a conductor 81 with contact 33 and conductor 72.

Let it now be assumed that the tank is filled with cold water and that contact arms 41 and 43 have just been moved into engagement by a continuously operative timing means so that the time is, say 10:00 P. M. Since the tank is full of cold water the bimetal arms 29 and 35 will be in engagement with their cooperating contact members 33 and 39 whereby an energizing circuit through heater 25 is closed traceable as follows: from supply circuit conductor 57, through the engaged contact arms 41 and 43, through conductor 61, bimetal bar 35, conductors 63 and 65, heater 25, conductor 72, through bimetal bar 29 and from there through conductor 73 to the second supply circuit conductor 59.

This energization of heater 25 will therefore cause heating up of the water in the tank and particularly the water in the upper portion of the tank, the water in the uppermost portion of the tank becoming hot substantially first. When the layer of cold water uppermost in the lower part of the tank has been dropped to a position where bimetal arm 35 is in heat-receiving relation with hot water in the tank, it will move out of engagement with contact 39 whereby de-energization of the electric heater 25 is effected.

A second heating circuit for the heating coil 55 was closed substantially at the same time, this circuit being traceable as follows: from supply circuit conductor 57, through the engaged contact arms 41 and 43, conductors 61 and 75, through heater 55, through that part of rheostat 77 which is in circuit, through conductor 81, through bimetal bar 29 and from there through conductor 73 to the second supply circuit conductor 59. As has already hereinbefore set forth, the amount of energy translated into heat in heating coil 55 is relatively small, the adjustment by means of the adjustable rheostat 77 being such that it will require about four hours or say until 2:00 P. M. before the contact bridging member 71 has been moved upwardly far enough to engage the contacts 67 and 69. If now the bimetal bar 35 is moved to open position whereby electric heater 25 is de-energized before contact bridging member 71 engaged contacts 67 and 69, the engagement of contact bridging member 71 with contacts 67 and 69 closed a second energizing circuit through heater 25 traceable as follows: from supply circuit conductor 57, through the engaged contact arms 41 and 43, through conductor 61, through the engaged contact members 69, 71 and 67, through conductor 65, heater 25, conductor 72, bimetal bar 29, which is still closed and from there through conductor 73 to the second supply circuit conductor 59.

The energization of heater 25 will therefore continue until substantially all of the water in the tank is hot, that is, has been heated to a temperature on the order of say 150° F. when bimetal bar 29 will move to open position whereby the heater coil 25 is de-energized, and it is assumed

that it will take less than four hours to heat all the rest of the water in the tank to a temperature of 150° F. If it does not heat all of the water in the tank before the contact arms 41 and 43 are disengaged, the time-controlled switch will effect de-energization of electric heater 25 whereby all of the parts may return to their normal or inoperative position.

The specific form of thermal retarder disclosed and claimed herein is effective to cause an adjustable but predetermined time period of delay in the energization of heater 25 after closure of the time-controlled switch hereinbefore described.

Various modifications may be made in the device embodying my invention without departing from the spirit and scope thereof and all such modifications clearly coming within the scope of the appended claims shall be considered as part of my invention.

20 I claim as my invention:

1. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expandable and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said electric heater being energized immediately upon closure of said time-controlled switch through said first and said second thermally-actuable switches and said time-controlled switch when said tank is full of cold water.

2. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expandable and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said electric heater being energized with a predetermined time period of delay after closure of said time-controlled switch, through said first thermally-controlled switch, the switch closed by

said bellows and the time-controlled switch, when said first thermally-controlled switch only is subject to cold water.

3. A water heater control system as set forth in claim 2 and including means for varying said predetermined time period of delay.

4. A water heater control system as set forth in claim 2 and including manually-actuable means for varying said predetermined time period of delay.

5. A water heater control system as set forth in claim 2 and including a manually-actuable rheostat connected in series with said electric heating coil for varying said predetermined time period of delay.

6. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expansible and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said electric heater being energized with a predetermined time period of delay after closure of said time-controlled switch, through said first thermally-controlled switch, the switch closed by said bellows and the time-controlled switch, when said first thermally-controlled switch only is subject to cold water, said first thermally-actuable switch de-energizing said electric heater when the tank is substantially full of hot water.

7. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expansible and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said first and second thermally-actuable switches and said time-controlled switch being connected in series circuit with each other and with said electric heater, the switch actuated by said bellows being connected in parallel cir-

cuit with said second switch, the energization of said electric heating coil being controlled jointly by said first thermally-actuable switch and said time-controlled switch, said electric heater being adapted to be energized immediately upon closure of said time-controlled switch, through said first and second switch and said time-controlled switch in case said first and second switches are both subject to cold water.

8. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expansible and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said first and second thermally-actuable switches and said time-controlled switch being connected in series circuit with each other and with said electric heater, the switch actuated by said bellows being connected in parallel circuit with said second switch, the energization of said electric heating coil being controlled jointly by said first thermally-actuable switch and said time-controlled switch, said electric heater being adapted to be energized with a predetermined time period of delay after closure of said time-controlled switch, through said first switch, said time-controlled switch and said switch actuable by said bellows in case only the first switch is subject to cold water.

9. A water heater control system for a hot water tank comprising an electric heater, said system comprising a first thermally-actuable heater circuit control switch adapted to be in heat-receiving engagement with water in the tank near the lower end thereof and to be in open position when subject to hot water and to be in closed position when subject to cold water, a second thermally-actuable heater circuit control switch adapted to be subject to the temperature of water intermediate the ends of a tank and to be in closed position when subject to cold water and to be in open position when subject to hot water, a thermal retarder heater circuit control switch unit comprising an elongated tubular member, an expansible and contractible bellows secured to one end of said tubular member, fluid in said tubular member, an electric heating coil on said tubular member, a heater circuit control switch adapted to be closed when said bellows has expanded a predetermined amount and an off-peak time-controlled heater circuit switch adapted to be closed during off-peak hours of a twenty-four-hour day, said first and second thermally-actuable switches and said time-controlled switch being connected in series circuit with each other and with said electric heater, the switch actuated by said bellows being connected in parallel cir-

cuit with said second switch, the energization of said electric heating coil being controlled jointly by said first thermally-actuable switch and said time-controlled switch, said electric heater being adapted to be energized with a predetermined time period of delay after closure of said time-controlled switch, through said first switch, said time-controlled switch and said switch actuatable by said bellows in case only the first switch is subject to cold water said first thermally-actuable switch de-energizing said electric heater when the tank is substantially full of hot water.

10. A water heater control system as set forth in claim 8 and including means for varying said predetermined time period of delay.

11. A water heater control system as set forth in claim 8 and including manually-actuable means for varying said predetermined time period of delay.

12. A water heater control system as set forth in claim 8 and including a manually-actuable rheostat connected in series with said electric heating coil for varying said predetermined time period of delay.

13. A water heater control system for a hot water tank comprising an electric heater, said system comprising a first thermally-actuable heater circuit control switch adapted to be in heat-receiving engagement with water in the tank and to be in open position when subject to hot water and to be in closed position when subject to cold water, a thermal retarder heater circuit control switch unit comprising an elongated tubular member, an expandable and contractible bellows secured to one end of said tubular member, fluid in said tubular member, an electric heating coil on said tubular member, a bellows-actuated heater circuit control switch adapted to be closed when said bellows has expanded a predetermined amount, circuit con-

ductors connecting said heating coil of said retarder in series with said first thermally-actuable control switch to be controlled thereby, and conductors connecting said electric heater of said tank and said bellows-actuated switch in series with each other and together in parallel with said heating coil, whereby said electric heater is adapted to be energized under control of both said first thermally-actuable control switch and said bellows-actuated switch of said retarder.

14. The combination of the immediately preceding claim wherein said first thermally-actuable heater circuit control switch has its heat-receiving engagement with the water near the

15 lower part of the tank, and wherein there is included, a second thermally-actuable heater circuit control switch adapted to be subject to the temperature of water at a position in said tank above that of said first thermally-actuable switch

20 and to be in closed position when subject to cold water and in open position when subject to hot water, said second thermally-actuable switch being connected in parallel with said bellows-actuated switch, whereby said retarder is ineffective for delaying energization of said electric heater 25 of said tank when said second thermally-actuable switch is subject to cold water.
